UNITED STATES PATENT OFFICE.

RICHARD D. FAY, OF NAHANT, MASSACHUSETTS, ASSIGNOR, BY MESNE ASSIGNMENTS,
TO HAMMOND V. HAYES, TRUSTEE, OF BOSTON, MASSACHUSETTS.

MAGNETO TELEPHONE.

Application filed April 13, 1922. Serial No. 552,325.

To all whom it may concern:

Be it known that I, RICHARD D. FAY, of Nahant, in the county of Essex and State of Massachusetts, a citizen of the United States, 5 have invented a new and useful Improvement in Magneto Telephones, of which the following is a specification.

I will take the case of an electro-magnetic telephone as the simplest illustration of the 10 application of my invention to a practical and useful purpose. It is well known that a telephone when used as a receiver must transform the alternating currents which are made to pass through the coil or coils of its 15 electro-magnet into a to-and-fro movement of a member which will produce the compressional waves in air which are called sound. The best receiver is one which will make this transformation from electrical 20 waves into air waves with the least possible loss in energy and will at the same time create sound waves as nearly as possible similar in form and relative intensity as the electrical waves which actuate it. Similarly 25 when the telephone is used as a transmitter for transforming air waves into electrical waves, the best form is that in which there is the least loss of energy in the transformation and in which there is the least distortion 30 in electrical wave form from that of the actuating air wave form.

Or, if the case of a quick-acting relay is considered, the design must be such as will offer the least possible loss or deformation 35 of the incoming electrical wave and at the same time create a motion of the moving part as quickly as possible and with the least possible loss of energy.

The well known form of Bell receiver 40 does not meet the requirements outlined above, both on account of its high effective resistance and from the fact that there are large losses in the magnetic circuit arising from the necessity of having a thin dia- 45 phragm, forming a portion of the magnetic circuit, and considerable separation between the pole pieces and the diaphragm. I am aware that attempts have been made to overcome these difficulties by the elimination 50 of the diaphragm as a portion of the magnetic circuit as has been done by supporting from the diaphragm a light coil or a tube of conducting material, said coils or tubes moving in a powerful magnetic field. 55 The weight of these moving parts and the

large air gap required in the magnetic field has resulted in little or no improvement in the sensitiveness of such devices when used as telephone receivers, although instruments of this type have one important advantage in that the amplitude of the moving parts is restricted only by the flexibility of the diaphragm to which they are attached. I am aware that another type of receiver 60 has been devised in which an armature, pivoted or hinged between the two poles of a magnet or electro-magnet, is used, such armature having one end connected with a diaphragm which does not form a portion of the magnetic circuit. This latter type 70 of receiver is sensitive, but is open to several defects which limit its effectiveness. An instrument of this type is that described in U. S. Patents No. 957,403, dated May 10, 1910, and No. 1,153,593, dated September 14, 75 1915.

My invention consists in improvements in this last type of magnetic receiver or transmitter, whereby greater sensitiveness is obtained with less distortion as well as a far 80 greater amplitude of motion of the sound-emitting member with less expenditure of energy.

My invention consists in an electro-magnet 85 in which the armature is normally substantially under no strains such as are imposed by springs or similar means and is free to move in a substantially uniform field with unrestricted amplitude as far as the magnet is concerned. 90

The armature of my electro-magnet, when no alternating current is acting upon it, is so balanced that there is no resultant longitudinal pull upon it.

In the drawings accompanying the present specification my invention is shown in its preferred form.

Figure 1 is a front elevation of my electro-magnet.

Fig. 2 is a section on line 2—2 of Fig. 1. 100
Fig. 2^a is a modification.

Fig. 3 shows the armature of my electro-magnet as blanked out.

Fig. 4 is a sectional view of a casing enclosing my electro-magnet when used in a 105 magneto telephone.

Fig. 5 is a plan of my electro-magnet.

1 is a spool of insulated wire for carrying the alternating currents used when the electro-magnet is actuated, its leads (not shown) 110

being connected with a suitable source of alternating current. 2 and 3 are pole pieces which pass, respectively, over and under the spool (see Fig. 2), being connected to the 5 horse-shoe magnet M by bars 21 and 31. 6 is the armature which is a thin plate of iron of high permeability which passes through the central opening in said spool 1. This 10 armature is punched or blanked as shown in Fig. 3 and then bent into the form shown in Fig. 2. The metal removed makes a rectangular hole at 7, leaving two narrow strips at 8 and 9, and when the armature is 15 bent into the form shown in Fig. 2, if the end 11 is held firmly and pressure applied at the end 10, the strips will bend easily and thus form practically a spring hinge for the armature. Thus the end 10 has great freedom of movement while there is relatively 20 small movement of the armature at the points where the strips 8 and 9 join the main body of the armature 6. The bent end 11 of the armature is held rigidly upon one of the pole pieces by four screws 12, 13, 14 and 25 15. Screw 12 is tapped into the pole piece and screws 13, 14 and 15 are tapped into the part 11, their ends resting against the pole piece.

The pole pieces 2 and 3 are extensions of 30 magnet M, and as shown are shaped to substantially surround the coil and form a narrow slit in which the armature may vibrate, the edges 4 and 5 being chamfered to direct the magnetic flux onto the armature.

35 An important feature of my invention lies in the relation which is made to exist between the pole pieces and the armature. To illustrate this relation, Fig. 2 is presented which is a cross section at 2—2 of Fig. 1. 40 See, also, Fig. 3 which shows the armature blank arranged in relation to one of the pole pieces. It will be seen that armature 6 can be brought into the closest proximity to the surfaces 4 and 5 of the pole pieces and, as 45

the pole pieces are slotted as at a to allow the projection 10 to move freely, the armature can travel to points within the chamber enclosed by the pole pieces, but it is so proportioned with relation to the pole pieces 50 that it will not touch them even when its movements are the greatest. As a result of this design the magnetic relations between 6 and 2, 3, 4 and 5 are substantially equal and as a consequence there is no longitudinal 55 strain exerted upon 6 by the magnet and its pole faces. Moreover, the magnetic fluxes through the armature are such that it is practically unmagnetized longitudinally and as a consequence the largest possible number 60 of lines of force will be induced in it by the alternating currents when passing through coil 1. If the alternating current at a given instant of time makes the armature North at its free end, it will be polarized South at 65 the end at which it is pivoted.

Theoretically strips 8 and 9 should be of non-magnetic material, but for mechanical reasons I have preferred to use the same material for these strips as that used in the armature and to eliminate losses by reducing the cross sections of the strips to a minimum consistent with the requisite mechanical strength. When the armature 6 is thus magnetized its free end will be pulled down 70 so that as many lines of force as possible will pass from it to the edge 5 of pole piece 3. On a reversal of the current in coil 1 the free end of the armature will be made South and will be attracted to the edge 4 of pole piece 2 with like result. 75

In Fig. 4 the general arrangement of my electro-magnet as applied to a telephone receiver is shown. In this drawing 16 is a diaphragma mounted within case 19. A stiff wire or small rod 20 has one end secured to 80 the armature tongue 10. The other end of the rod is threaded and the rod is attached to diaphragm 16 by nuts 17 and 18. Thus the movements of the armature are imparted to the diaphragm. 85

The magnet may be a permanent or electro-magnet as desired and other changes from the construction shown in the drawings may be made without departing from the subject-matter of my claims. 90

My invention is particularly adapted to electro-magnets in such forms as are used in quick-acting relays.

I have found that a very efficient way of supporting the armature is that shown in 100 Fig. 2^a where as shown at 32 a piece of elastic material such as soft rubber is placed between the armature and the pole piece and a second like piece of material is placed outside the armature. 33 is a metal piece or 105 washer. A screw 12 passes through this washer and the members 32 as well as through the armature and holds the armature to the pole piece.

What I claim as my invention is:

1. A device of the kind described comprising a field magnet having pole pieces located to form two short air gaps in the magnetic circuit, means for supporting an armature and an armature attached at one end to said supporting means whereby its other end may swing freely, said pole pieces being located on opposite sides of said armature, said armature being located in said gaps and shaped to be free at all times from contact with the pole pieces forming said gaps. 110

2. A device of the kind described comprising a field magnet, the poles of which are located to form two short air gaps in the magnetic circuit, an armature pivoted at one end and located between said pole pieces to cut both said air gaps whereby it is normally maintained in balanced relation, a member to be vibrated, and means connecting said member with the free end of said armature. 120 125

3. In a device of the kind described, a magnet the poles of which are located to form two gaps of different length in the magnetic path, an armature located between 5 said gaps with one end projecting into the longer of said gaps and with the other end overlapping the pole pieces at the shorter gap, said armature being hinged near the projecting end.
- 10 4. In a device of the kind described, an electro-magnet responsive to alternating currents, having a normally longitudinally unmagnetized armature pivotally mounted near one end thereof, a field magnet, the 15 other end of said armature being located in close proximity to two pole faces of said field magnet of opposite polarity, said pole faces and said other end of said armature being shaped with relation to each other 20 whereby said armature may be given an amplitude of vibration mechanically unrestrained by said poles.
5. An electro-magnet having an armature hinged near one end, an alternating current 25 coil located to surround the free portion of said armature, a field magnet having recessed pole pieces located to partially enclose said coil, the free end of said armature being proportioned to vibrate within the recesses 30 in said pole pieces.
6. A magneto-telephone comprising a diaphragm and means by which it is actuated
- comprising a magnet and an armature, said magnet comprising a coil located between the two pole pieces of said magnet, said pole 35 pieces being in close proximity to each other, one end of said armature being attached to one of said pole pieces and the other end thereof lying within the coil and between the surfaces of said pole faces adjacent to 40 the coil.
7. A field magnet, an armature, a mounting therefor engaging one end thereof whereby the other end of said armature is free to vibrate, a coil surrounding said armature, 45 the poles of said magnet being recessed and said armature being located to vibrate within said recesses.
8. A magneto-telephone comprising a diaphragm and means by which it is actuated 50 comprising a magnet and an armature, said magnet comprising a coil located between the two pole pieces of said magnet, said pole pieces being in close proximity to each other, one end of said armature being attached to 55 one of said pole pieces and the other end thereof lying within the coil and between the surfaces of said pole faces adjacent to the coil, said armature-attracting means comprising a clamp having two pieces of 60 soft elastic material, one located on each side of said end and means for clamping said elastic material and said end to its pole piece.

RICHARD D. FAY.
